(57) **CLAIM**

The ornamental design for "a curved tint brush," as shown and described.

DESCRIPTION

FIG. 1 is a generally perspective view of a curved tint brush showing my new design;

FIG. 2 is a side elevational view thereof;

FIG. 3 is a right end view thereof;

FIG. 4 is a left end view thereof;

FIG. 5 is a top view thereof; and,

FIG. 6 is a bottom view thereof.

The broken line structure shown in FIG. 1 is for illustrative purposes only and forms no part of the claimed design.
